(57) **CLAIM**

The ornamental design for a display for dishwasher, as shown and described.

DESCRIPTION

FIG. 1 is a front view of a display for dishwasher showing my new design;

FIG. 2 is a front view of an alternate configuration thereof, and,

FIG. 3 is a front view of another alternate configuration thereof.

The broken line showing of the display screen is for the purpose of illustrating environmental structure and forms no part of the claimed design.
